UNITED STATES PATENT OFFICE

WINFIELD S. GRANT AND FRANCIS H. SHOOP, OF DETROIT, MICHIGAN

FIRE POT FOR OIL BURNERS

Application filed May 20, 1930. Serial No. 454,125.

This invention relates to oil burners and particularly to fire pots thereof.

The main objects of the invention are to provide a fire pot of improved construction having means for vigorously turbulating a physical mixture of air and oil so as to produce a substantial absorption of air by the oil; to provide a refractory lining in a fire pot of this kind which has a fuel and air inlet and a registering recess for receiving the supply of oil and air; to provide an improved nozzle for discharging fuel and air into the recess; to provide a recess of this kind which is formed so as to direct the fuel and air supply as it leaves the recess in a course following the curvature of the side wall of the lining; to provide an end wall in a recess of this type which extends transversely of the path of the incoming oil and air forming a baffle against which the oil and air supply is directly impinged so as to recirculate and turbulate the same; and to provide a side wall in the fuel and air receiving recess which has an inner end portion that is adapted to spread the flame resulting from combustion of the fuel evenly around the periphery of the fire pot at the open end thereof.

A further object of this invention is to provide a fire pot lining which includes a pair of convenient, precast sections.

An illustrative embodiment of the invention is shown in the accompanying drawing, in which:

Fig. 1 is a top plan view partly in section of a fire pot embodying our invention.

Fig. 2 is a vertical section taken on the line 2—2 of Fig. 1.

In the form shown my improved burner includes a broad, shallow, outer bowl 1; preferably comprising metal, having a bottom wall 2 and a spout or throat 3 on its side. Extending through the throat 3 is a passage which communicates with an inlet aperture 4 in the side wall of the bowl. The burner is supported on a pedestal 5 which is received in an aperture of a bracket 6 having a bolt 7 threaded therein by means of which the bowl is held at a selected elevation.

Seated in the outer bowl 1 is an inner bowl 8 preferably formed of high temperature heat

resisting, refractory material which forms a lining. The inner bowl 8 includes upper and lower sections 9 and 10, each having a side wall portion. The edge of the side wall portion 10 of the lower section has a groove 11 formed therein and the edge of the side wall of the upper section 9 has a tongue 12 which is seated in the groove 11 of the lower section. These sections are cast separately and are cemented together at the adjacent edges of their side wall portions by high temperature resisting cement when assembled together.

Formed on the upper end of the section 9 is a peripheral flange 13 which extends inwardly, restricting the open end of the inner bowl 8 somewhat. The lower section 10 of the lining has a bottom wall 14 in which a recess 15 is provided, and the side wall of the inner bowl has an inlet opening 16 which registers with the inlet opening 4 of the throat 3 of the outer bowl. The inner end and intermediate portion of the outer side wall 17 of the recess 15 substantially coincides with the inner periphery of the side wall of the bowl 8. The recess 15 is located in registration with the inlet opening 16 and the end portion 18 of the outer side wall of the recess is substantially tangent to the inner periphery of the bowl 8. The inner side edge portion 19 is substantially parallel to the edge portion 18 of the recess, between the inner extremity of the inlet aperture 16 with which it registers and the diameter, indicated by dotted line 20 which is normal to the edge portion 18 of the recess. The side edge 21 of the recess 15 which extends inwardly from the diameter 20 is inclined relative to the edge portion 19 as shown in Fig. 1, for the purpose of distributing the flame resulting from the combustion of fuel in the burner, evenly around the flange 13. Formed at the inner extremity of the recess 15 is a wall or shoulder 22 which serves as a baffle for turbulating fuel when the latter is discharged into the recess. The impingement of the fuel against the end wall 22 at a high velocity causes it to change its direction of flow and some of the fuel rebounds into the main stream of fuel and air issuing from the nozzle.

A fuel and air nozzle 23 extends through

the throat 3, apertures 4 and 16, and into the interior of the bowl 8. The nozzle 23 is positioned at an inclination to the bottom wall 14 of the lining 8 and its discharge end extends 5 into the recess 15. Communicating with the outer end of the nozzle 23 is an air and fuel supply conduit 24 through which both air and fuel are supplied by a fan or other suitable means, not shown.

10 In operation, the air and fuel which is discharged into the recess 15 through the nozzle 23 impinges or strikes the shoulder 22 by which it is turbulated and rebounded into the main flow of air coming from the nozzle, 15 thereby causing the fuel, in the form of oil, to absorb substantial quantities of air. The fuel and air are directed by the recess 15 in a current which follows the curvature of the flange or diaphragm 13, and the side edge 20 portion 21 of the recess which is inclined with respect to the edge portion 19, it is found, causes the flame which results from combustion of the fuel to spread evenly as it emerges from the burner around the diaphragm 13.

25 By providing precast sections of refractory material in the construction of the lining, the molding of the latter is materially simplified. These sections are separately cast and later assembled and cemented together 30 before installation in the outer bowl 1. In some instances it may be found desirable to separately place the sections 9 and 10 in the outer bowl 1 and cement them together therein.

35 Although but one specific embodiment of this invention has been herein shown and described, it will be understood that numerous details of the construction shown may be altered or omitted without departing from the 40 spirit of this invention as defined by the following claims.

What we claim is:—

1. A burner fire pot including a bowl generally circular in section parallel to its bottom wall having a recess in the inner side of its bottom wall and adjacent its side wall and a registering inlet opening, and a nozzle extending through said opening tangentially to its side wall and into said recess at an inclination to said bottom wall for discharging fuel into said recess.

2. A burner fire pot including a bowl generally circular in section parallel to its bottom wall having a recess in the inner side of its bottom wall and a registering inlet opening in its side wall, one side edge of said recess being substantially adjacent the inner surface of the side wall of said bowl, and a fuel nozzle extending through the opening at a tangent to said side wall having a portion of its outlet end inclined to said bottom wall and below the open side of said recess.

3. A burner fire pot including a bowl generally circular in section parallel to its bottom wall having a recess in the inner side of

its bottom wall and adjacent its side wall and a registering inlet opening, and a fuel nozzle extending through said opening for discharging fuel into said recess, the end wall of said recess extending in a generally radial direction with respect to said bowl and forming a baffle for turbulating said fuel.

4. A burner fire pot including a bowl generally circular in section parallel to its bottom wall having a recess in the inner side of its bottom wall and adjacent its side wall and a registering inlet opening, and a nozzle extending through said opening tangentially to its side wall and into said recess at an inclination to said bottom wall for discharging fuel into said recess, and said recess having an end wall at its inner extremity of said recess extending substantially transversely of the flow of fuel therein for turbulating the fuel.

5. A burner fire pot including a bowl generally circular in section parallel to its bottom wall having an open upper end and a side inlet opening, an inwardly extending flange on the upper end of said bowl constricting the opening therein, the bottom wall of said bowl having a recess in its inner surface registering with said inlet opening and located directly below said flange, and a nozzle extending through said inlet opening and into said recess tangential to the side wall for discharging fuel into the latter, said recess having an upstanding end wall in the path of the fuel flow therein for turbulating said fuel.

6. A burner fire pot including a metal casing having an inlet throat, a bowl generally circular in section parallel to its bottom wall in said casing comprising refractory material and having an opening registering with said inlet throat, the bottom wall of said bowl having a recess therein registering with said opening and coinciding at one edge with the side wall of said bowl, and a nozzle inclined to its bottom wall mounted in said inlet throat having its outlet end in said recess tangential to the side wall for discharging fuel thereinto.

7. A burner fire pot including a metal casing having an inlet throat, a bowl generally circular in section parallel to its bottom wall in said casing comprising refractory material and having an opening registering with said inlet throat, the bottom wall of said bowl having a recess therein registering with said opening, said recess having an outer wall aligned with an extending along the side wall of said bowl, and a nozzle mounted in said inlet throat having its outlet end in said recess tangential to the side wall for discharging fuel thereinto, said recess having an inner end wall extending transversely of and in the path of flow of fuel from said nozzle and forming a baffle for turbulating said fuel.

8. A burner fire pot including a bowl generally circular in section parallel to its bottom wall having an open upper end and a bottom wall having a recess adjacent the side wall therein, and means extending into said bowl in registration with said recess generally inclined to the bottom wall and tangential to the side wall for discharging fuel and air thereinto, the inner end portion of the inner side edge of said recess being inwardly inclined with respect to the remaining portion of said side edge so as to evenly spread the flame resulting from combustion of said fuel around the periphery of the open top of said bowl.

9. A burner fire pot including a bowl generally circular in section parallel to its bottom wall having an open top and a bottom wall having a recess adjacent the side wall therein, and means extending into said bowl in registration with said recess for discharging fuel and air thereinto, said recess having an upstanding end wall in the path of said fuel and air for turbulinating the same as it leaves said recess and the inner side of said recess having converging portions for distributing the flame resulting from combustion of said fuel.
